TIMING DEVICE

Georges Ducommun, Grenchen, Switzerland, assignor to
Baumgartner Freres S. A., Grenchen, Switzerland

Application April 27, 1954, Serial No. 30,204

Term of patent 14 years

(Cl. D42—8)

FIG.1

FIG.3

FIG.2

FIG.4

To all whom it may concern:

Be it known that I, Georges Ducommun, a citizen of Switzerland, residing at Tannhofstrasse 27, Grenchen, Switzerland, have invented a new, original, and ornamental Design for a Timing Device, of which the following is a specification, reference being had to the accompanying drawing, forming a part thereof.

Figure 1 is a front view of the timing device.
Figure 2 is a rear view of the timing device.
Figure 3 is a side view of the timing device.
Figure 4 is a rear perspective view.

I claim:
The ornamental design for a timing device, substantially as shown.
